UNITED STATES PATENT OFFICE

2,003,346

REVERSIBLE RATCHET WRENCH

John S. Dodge, Paxton, Mass., assignor to Harry Sinclair, John H. Dodge, both of Worcester, Mass., and Louis C. Smith, Newton Center, Mass., as trustees

Application March 30, 1934, Serial No. 718,180

2 Claims. (Cl. 81—62)

This invention relates to reversible ratchet wrenches, reversible ratchet sleeve twisters and the like, and it has for its object to provide improvements in the pawl-reversing devices of reversible ratchet tools of this nature.

In order to give an understanding of the invention I have illustrated it as embodied in a reversible ratchet wrench of the closed end type, but I wish to state that the invention is equally applicable to open-ended reversible ratchet wrenches and to reversible ratchet sleeve twisters and other similar reversible ratchet tools.

In the drawing, Fig. 1 is a view of a reversible ratchet wrench embodying my invention, a part 15 of the handle being shown in section, and the cover plate removed;

Fig. 2 is a section on the line 2—2, Fig. 1;

Fig. 3 is a section on the line 3—3, Fig. 1;

Fig. 4 is a fragmentary perspective view of 20 one end of the pawl-reversing rock shaft;

Fig. 5 is a perspective view of the pawl-reversing member;

Fig. 6 is a section on the line 6—6, Fig. 1;

Fig. 7 is a view illustrating a different embodiment of the invention.

In some respects the wrench herein shown is an improvement on the ratchet wrench illustrated in Patent No. 1,177,764 and also in the sleeve twisters shown in Patents No. 1,890,213, 30 December 6, 1932 and No. 1,929,678, October 10, 1933.

The wrench herein shown is of that type having a body member 1 which presents a handle portion 2 and a head portion 3, the latter being 35 provided with a socket receiving recess 4 in which is received the rotary socket member 5. This socket member 5 is provided on its periphery with teeth 6 which co-operate with pawls 7, 8. The pawls 7 and 8 are oppositely disposed, one 40 pawl being operative for rotating the socket member in one direction and the other pawl being operative for rotating the socket member in the opposite direction. Each pawl is provided with the cylindrical bearing portion 9 which is received in the correspondingly-shaped recess 10. Each pawl is also acted on by a spring 11 which tends to throw it into operative engagement with the socket member 5 as usual in ratchet wrenches of this type.

50 The present invention relates particularly to the means for reversing the pawls, that is, to the means for throwing either pawl into inoperative position out of engagement with the socket member 5.

55 Extending longitudinally of the handle is a

rock shaft 12, the outer end of which is supported in a suitable bearing in the end of the handle, and the other end of which extends through and has bearing in an aperture 15 formed in the portion 16 of the body. In one form of the invention the outer end of the handle is closed by a plug 14 which fits a recess formed in the end of the handle with a driving fit and which forms a bearing for the end 13 of the handle. In another form of the invention the end 10 of the rock shaft 12 has a head 40 secured thereto which finds a bearing in the end of the handle and which is provided with a knurled finger piece 41 by which the rock shaft can be turned.

The shaft 12 has fast thereon a pawl-reversing member 17 which is received in a recess 18 formed in the portion 16 of the body member. As herein shown the end 19 of the shaft 12 is sector shaped and the pawl-reversing member 17 is provided with a similarly-shaped aperture 20 20 into which the sector-shaped end of the shaft 12 extends. The shaft 12 is also shown as provided with an annular groove 21 which receives a locking pin 22 carried by the portion 16 of the body member, said pin serving to hold the shaft from longitudinal movement while allowing it to be turned freely.

The pawl-engaging member 17 is formed with two flat faces 23, 24 which are situated less than 180° apart and in the construction shown in Figs. 1 and 2 the shaft 12 is provided with a pin or projection 25 which extends through an opening 26 formed in the cover plate 27 and by which the shaft 12 may be turned. In the construction shown in Fig. 7 the rock shaft is turned through the medium of the knurled finger piece 41 instead of by means of the pin 25.

When the pawl-reversing member 17 is in the position shown in Figs. 1 and 3 the flat face 24 thereof engages the flat face 28 of the pawl 7, thereby holding said pawl in its retracted position out of engagement with the socket member 5. When the pawl-engaging member is in this position the other flat face 23 will be sufficiently removed from the pawl 8 so that said pawl will occupy its operative position in engagement with the socket member 5 as shown in Fig. 1. When the projection 25 is swung to the dotted line position Fig. 3 the pawl-reversing member will engage the pawl 8 thereby forcing it in its inoperative position and the same movement will withdraw the pawl-reversing member from engagement with the pawl 7 thereby allowing it to move forwardly into operative position.

In either of the extreme positions of the pawl-reversing member 17 one of the flat faces thereof engages the flat face 28 of the pawl and the pressure of the spring against the pawl holds 5 these flat faces in contact with sufficient force to prevent the shaft 12 from accidental turning movement. As the shaft is turned from the full to the dotted line position Fig. 3 to reverse the pawls the corner 29 of the pawl-reversing member 17 swings in the arc of a circle and forces the pawl 7 back slightly while the corner 30 by its engagement with the face 28 of the pawl 8 will force said pawl back towards its inoperative position. During the turning movement of the 15 pawl-reversing member the corner 30 will force the pawl 8 back slightly beyond the normally-retracted position shown in Fig. 1 and as the face 23 of the pawl-engaging member comes into a position parallel to that of the face 28 of the 20 pawl 8, said pawl will move forwardly slightly under the influence of its spring 11. This gives a sort of snap action to the operation of the pawl-reversing member so that the operator can easily determine by the feel of the pawl-reversing 25 member when said member is in its proper position.

This construction has the further advantage which has been referred to above, that it serves to yieldingly hold the pawl-reversing member in 30 either of its extreme positions without the use of an extra part for this purpose, such as the spring shown in the patents above referred to. In the construction shown the sector-shaped portion 19 of the shaft 12 is non-axially situated 35 with reference to said shaft. This construction has been adopted so that the under surface 31 of the pawl-reversing member will be situated above the bottom 32 of the recess 18.

While I have illustrated the invention as applied to a ratchet wrench of the closed end type 40 yet it will be obvious that the invention is equally applicable to open-ended reversible ratchet wrenches or to reversible ratchet tools of the sleeve twister type such as shown in the above-mentioned Patents No. 1,890,213 and No. 1,929,678.

In the manufacture of sleeve twisters for use 50 in splicing wires of electric transmission lines it is desirable that the handle should be provided with a coating of insulation. One way of providing such insulation is to dip the handle in an insulating compound while in liquid condition, such dipping providing the handle with the desired coating of insulating material. The construction herein illustrated is admirably adapted 55 for this method of insulating the handle.

The fact that the bearing member 14 is driven 60 into the end of the handle with a driving fit makes a perfectly tight joint at this point so that the handle can be dipped into the insulating material clear up to the cover plate 27 without any

possibility of any of the insulating material getting into the interior of the wrench to interfere in any way with the operation of the parts.

In the above description and in the claims I have used the term "socket member" as referring 5 either to the closed socket member such as the member 5 herein illustrated or the open or slotted member, such as is used in the tools of the sleeve twister type illustrated in the above-mentioned 10 patents.

I claim.

1. A reversible ratchet tool having a handle portion, a socket-receiving portion provided with a slot in its side face, a socket member rotatable in the socket-receiving portion, two oppositely-disposed pawls pivotally carried by the socket-receiving portion and co-operating with the socket member, each pawl having a flat face, a spring acting on each pawl, a rock shaft extending lengthwise of the handle portion and at right angles to the pawl axes, a pawl-reversing member fast on said rock shaft and having two flat pawl-engaging faces spaced less than 180° apart, there being one face for each pawl, an arm fast to the rock shaft and extending through said slot for 20 turning the shaft to bring each flat face of the pawl-reversing member into engagement with the flat face of the corresponding pawl, whereby said pawl is held in inoperative position, the pressure of the flat face of the pawl against the flat 25 face of the pawl-reversing member due to the action of the spring serving to yieldingly hold the shaft and pawl-engaging member in its adjusted position.

2. A reversible ratchet tool having a handle portion, a socket-receiving portion, a socket member rotatable in the socket-receiving portion, two oppositely-disposed pawls co-operating with the socket member, a spring for each pawl, each pawl having a flat face, a rock shaft extending longitudinally of the handle, a plug closing the end of the handle and forming a bearing for one end of the rock shaft, said socket-receiving portion having a bearing portion to receive the other end of the rock shaft, which bearing portion is provided with a recess open at one face of said socket-receiving portion, a pawl-reversing member fast on said rock shaft and occupying said recess, said pawl-reversing member having two flat pawl-engaging faces spaced less than 30 180° apart, there being one face for each pawl, a slotted plate removably secured to a side face of said socket member and closing said recess, a projection extending from said shaft through said slot by which the shaft is turned to bring either flat face of the pawl-reversing member 35 into engagement with the flat face of the corresponding pawl, whereby said pawl is held in its inoperative position.

JOHN S. DODGE. 60
